UNITED STATES PATENT OFFICE.

JOHN M. YOUNG, OF BROOKLYN, NEW YORK, ASSIGNOR TO AMERICAN CAN COMPANY, OF NEW YORK, N. Y., A CORPORATION OF NEW JERSEY.

COMPOUND LINING HEAD.

Application filed October 17, 1921. Serial No. 508,102.

The present invention has to do with apparatus for and a process of lining the flanges of can ends with compound gasket material, and relates more particularly to 5 means for applying such material to the can ends in liquid form and in measured quantities.

A principal object of the invention is the provision of a process and an efficient and 10 commercially practicable apparatus for first withdrawing measured charges of material from a source of supply and then transferring said charges to distributing means adapted to maintain constant operative position with respect to the can end to be lined.

A further object of the invention is the provision of an improved and simplified apparatus for the purpose of evenly distributing gasket lining material in measured quantities upon the flanges of can ends in certain manner and with the use of a minimum number of operative parts.

Still another object of the invention is the provision of a process for lining the 25 flanges of can ends and a structure for carrying out such process whereby the material may be positioned in accurate amount upon various parts of the can end flange and distributed in more even fashion than has been 30 found possible with other processes and apparatus.

Another and highly important object of the invention is the provision, in apparatus for the purpose stated, of an intermediate 35 measuring member adapted to receive measured charges of material from a source of supply and subsequently acting distributing means adapted to receive said charges and apply the same to the can ends in particularly effective manner.

A still further object of the invention is the provision of mechanism for lining can ends in which the ends may be fed into position to be lined, the lining material with- 45 drawn in measured quantities from a source of supply and said measured quantities applied to the flanges of the can ends through the use of single power means and a minimum number of power transmitting members.

Numerous other objects and advantages of the invention will be apparent as it is better understood from the following, which, taken in connection with the accompanying

drawings, discloses a preferred embodiment 55 thereof.

Referring to the drawings,

Figure 1 is a transverse vertical section taken centrally through a machine embodying the principles of my invention; 60

Fig. 2 is a plan view of the machine with the lining head removed;

Fig. 3 is an enlarged partial section taken substantially on the line 3—3 of Fig. 2, and showing the driving mechanism by which 65 the machine is operated;

Fig. 4 is a detail section of the operating cam for the end feed mechanism;

Fig. 5 is an enlarged sectional view taken vertically through the lining head substantially upon the line 5—5 in Fig. 1; 70

Fig. 6 is a sectional plan view of a reservoir and feeding mechanism for the lining material, and is taken substantially on the line 6—6 in Fig. 5; and 75

Fig. 7 is a fragmentary detail view of one of the distributing rollers and is taken substantially on the line 7—7 in Fig. 6.

Upon the drawings, comprising an illustrative embodiment of my invention, I have 80 shown a table 11 upon which is supported a lining head 12 and a can end stack holder 13. The table 11 is supported upon a body frame 14 in which is positioned the operating mechanism to be hereinafter described, 85 and which is in turn supported upon a base 15. The can end stack holder comprises a plurality of posts or upstanding rods 16 and mechanism is provided therebeneath for singly selecting one of the can ends 17 from 90 the bottom of the stack and transferring it to a can end support 18 positioned beneath the lining head 12. This mechanism comprises a slide 19 operating between guideways 21 on the upper part of the table 11 95 and actuated by a cam 22 through an arm 23, a lever 24 and a link connection 25. The arm 23 has a bifurcated end or yoke 26 engaging an operating shaft 27 and carrying a roller adapted to engage in a groove 28 in the cam 22 to operate the can end feed slide 19. The arm 23 is adjustable by means of a threaded connection 29 and is pivoted at 31 onto the lever 24 which in turn is pivoted at 32 onto a punctured lug 33 extending upwardly from the base 15. It will be observed that in this manner the end feeding mechanism is operated in timed relation-

ship with respect to the lining head operating mechanism, and it will be understood that this part of the mechanism may be of any well known or preferred form to 5 accomplish the end just stated.

The lining head is supported upon the table 11 by a suitable bracket 34 and has therein a reservoir 35 adapted to contain a quantity of gasket lining material 36. An 10 entrance pipe 37 for the lining material is provided in one side of a cover member 38, which member has screw threaded engagement with the wall 39 of the reservoir, and an air pipe 41 is provided at another point 15 in the cover for admitting air to maintain a pressure in the reservoir. In the bottom of the reservoir are openings 42 spaced at intervals and arranged, in the present instance, around a circular path and 45° apart. 20 A gear 43 is arranged immediately beneath the bottom of the reservoir and has chambers 44 located therein in a manner corresponding to the arrangement of the apertures 42, with which said chambers are 25 adapted to register at given points in the path of rotation of said gear. A body part 45 of the lining head is secured by pins 46 to the lower part of the reservoir and is cut away near the top at 47 to provide a bearing 30 for the gear 43. Spaced about this body part in the same circular path in which the apertures 42 and the chambers 44 are arranged are distributing rollers 48 rotatably mounted on pins 49 having bearing in the 35 body 45 and immediately above these rollers are openings 51 adapted to register with the chambers 44 at given intervals in the rotation of the gear 43. The gear 43 is driven intermittently by a mutilated gear 52 having teeth 53 on a relatively small portion 40 only of its periphery, this driving gear being mounted upon an auxiliary shaft 54.

Referring now to Fig. 3, it will be noted that the drive shaft 27 carries a pulley 55 45 by which it is driven, and also carries the cam 22 by which the cover feeding mechanism is operated, and gearing, to be now described through which the lining head and the can end support are operated. A bevel gear 56 is secured on the drive shaft near its bearing 57 in the frame 14 and is in constant mesh with a smaller bevel gear 58 carried on the lower end of the shaft 54. The relative size of these two gears is such that 55 the shaft 54 turns twice for every single revolution of the shaft 27, and the gear 52 has just enough teeth to move the gear 43 the necessary 45° to first move the chambers 44 from position in registration with the apertures 42 to registration with the openings 51, and to again establish communication between one of the apertures 42 and the chambers 44 on the next subsequent revolution of the gear 52. It will thus be seen 60 that the relative size of the gears 56 and 58

results in the measuring gear 43 coming to rest twice and being moved twice during one cycle of operation.

Another bevel gear 59 is secured on the drive shaft 27 and meshes with a smaller 70 bevel gear 61 carried on the lower end of a shaft 62 which is secured at the upper end thereof by a screw threaded engagement at 63 to a can end support 18. The shaft 62 is reciprocable by means of a bell crank 64, 75 one arm 65 of which has engagement with a grooved collar 66, and the other arm 67 of which carries a roller 68 engaging in a cam groove 69 in a cam member 71 carried on the shaft 27. In this manner the can 80 ends which are successively fed onto the support 18 are lifted, after being so positioned, to the rollers 48 to have the gasket lining material distributed in the flange 72. It will be observed that the application of 85 the material takes place at different points in the periphery of the flange and the rotating of the end accomplishes even distribution entirely around the peripheral edge of the end. After being lined, the end is 90 ejected in any suitable or usual manner and another is fed onto the support 18 in the manner hereinbefore described.

The shafts 62 and 54 are supported in bearing members 73 and have bearing at 95 their upper ends in the table 11 in any preferred manner. A spring 74 is secured in a collar 75 extending through an aperture 76 in the lining head and exerts tension upon a rod 77 carrying a ball 78 adapted to contact with and to yieldingly resist upward movement of the can end 17.

With the mechanism just described, the lining material, which ordinarily is a compound of relatively thin liquid form, may be 105 first completely withdrawn in measured quantities from the source of supply and subsequently transferred by exact predetermined steps to the distributing means by which it is evenly applied about the can end 110 flange. This results in rapid, accurate and economical lining of the ends without any waste of material and precludes the possibility of uneven distribution.

It is thought that the invention and many 115 of its attendant advantages will be understood from the foregoing description, and it will be apparent that various changes may be made in the form, construction and arrangement of the parts without departing 120 from the spirit and scope of the invention or sacrificing all of its material advantages, the form hereinbefore described being merely a preferred embodiment thereof.

I claim:

1. An apparatus for lining the flanges of 125 can ends with gasket material, comprising means for supporting and rotating a can end, a head having a reservoir for gasket material therein, a measuring member having a plu- 130

- rality of measuring chambers adapted to receive charges of material from said reservoir and having means for intermittently cutting off the supply of gasket material to 5 a roller, and a roller adapted to subsequently receive said charges from the measuring member and apply the same to the can ends.
2. An apparatus for lining the flanges of can ends with gasket material, comprising a 10 rotary support for can ends, a head mounted above said support and having a reservoir for gasket material therein, measuring means embodying a plurality of measuring chambers adapted to receive at intervals predetermined charges of the gasket material from said reservoir, and having means for intermittently cutting off the supply of gasket material to a roller, and a roller adapted to receive said material from said measuring 15 means and apply the same to a can end.
3. An apparatus for lining the flanges of can ends with gasket material, comprising a rotary support for can ends, means for feeding can ends individually and successively to 20 said support, an applying head positioned above said support and having a reservoir for gasket material therein, rotary means concentric with said support for abstracting measured quantities of said material from 25 said reservoir, and means for receiving and distributing said measured quantities upon the flanges of a can end.
4. An apparatus for lining the flanges of can ends with gasket material, comprising 30 means for supporting and rotating a can end, a reciprocating can end support, an applying head positioned above said support, said head comprising a reservoir for gasket material, means for withdrawing gasket material from said reservoir in measured quantities, and rollers located under said withdrawing means and above said can end support for receiving said measured quantities of material intermittently from said last 35 mentioned means and applying the same to the flanges of a can end.
5. An apparatus for lining the flanges of can ends with gasket material, comprising a support for a can end and means for turning the same, an applying head positioned 40 above said support and comprising a receptacle for gasket material, a rotatable measuring member adapted to receive at intervals measured quantities of material from said receptacle, and distributing means adapted to receive the material from said measuring member and apply the same to the flanges of a can end.
6. An apparatus for lining the flanges of can ends with gasket material, comprising a 45 can end support and means for turning the same, a source of supply for gasket material, a measuring member having intermittent partial rotation for receiving at intervals measured quantities of said material from the source of supply, and applying means adapted to receive the material from the measuring member and apply the same to the flanges of the can ends.
7. An apparatus for lining the flanges of can ends with gasket material, comprising a rotary can end support, means for feeding can ends individually and successively to said support, and an applying head for distributing measured quantities of said gasket material upon the flanges of the can ends, 50 said head comprising a receptacle for the gasket material having ports in the bottom thereof, a rotary measuring member beneath said receptacle and having chambers therein adapted to register at given points with the ports in said receptacle, and distributing means adapted to receive measured charges of material from said chambers and deposit the same about the peripheral edge of the can end.
8. An apparatus for lining the flanges of can ends with gasket material, comprising a can end support and means for turning the same, a source of supply of gasket material above said support, a rotatable measuring gear having chambers therein for receiving at intervals measured quantities of gasket material from said source of supply, a mutilated driving gear for imparting intermittent partial rotation to said measuring gear, and distributing means adapted to receive the material at given points in the rotation of said measuring gear and distribute the same around the flange of a can end.
9. An apparatus for lining the flanges of can ends with gasket material, comprising a reciprocating rotatable can end support and means for turning the same, an applying head positioned above said support and having means therein including a rotary measuring chamber for withdrawing measured quantities of gasket material from a source of supply, and rollers for subsequently receiving and applying said measured quantities of material to the flange of a can end.
10. An apparatus for lining the flanges of can ends with gasket material, comprising a rotary can end support, mechanism for individually and successively feeding can ends to said support, a receptacle for the gasket material having openings at predetermined points in the bottom thereof, a rotary measuring member having chambers adapted to register at intervals with the openings in the bottom of said receptacle to receive measured quantities of said material, and means adapted, upon further rotation of said measuring member, to receive the material from said chambers and distribute the same upon the flange of a can end.
11. A process of lining the flanges of can ends with gasket material, which comprises delivering the material to measuring chambers of a rotary feeding device and subse- 130

quently transferring the material from said chambers to distributing means and applying the same to the flange of a can end while rotating the latter around an upwardly and downwardly extending axis.

12. A process of lining the flanges of can ends with gasket material, which comprises positioning a can end upon a rotary support and delivering the gasket material to

10 measuring chambers of an intermittently rotatable measuring member and delivering the measured charges of material from said chambers to distributing means and spreading same upon the flange of a can end.

15 13. A process of lining the flanges of can ends with gasket material, which comprises positioning a can end upon a rotary support, delivering the gasket material to measuring chambers of an intermittently rotatable measuring member and delivering the measured charges of material to a plurality of distributing elements.

20 14. A process of lining the flanges of can

ends with gasket material which consists in removing from the bottom of a mass of gasket material in horizontal circular directions intermittently and in measured quantities portions of the same, and then delivering said portions downward and positively conveying them to and applying them on the 30 surface of a can end and rotating the can end to receive such positively applied portions of the gasket material.

15. A process of lining the flanges of can ends with gasket material, which comprises 35 placing the material in a receptacle having apertures in the bottom thereof, rotating a measuring member beneath said receptacle to bring chambers in said member into registration with said apertures to receive measured charges of said material, further rotating said member to transfer said charges to distributing means and positioning a can end to permit distribution of said charges upon the flange thereof.

JOHN M. YOUNG.
